A. F. VICTOR

METHOD OF DELIVERING ILLUSTRATED LECTURES OR SONGS

Filed March 1, 1922

UNITED STATES PATENT OFFICE.

ALEXANDER FERDINAND VICTOR, OF NEW YORK, N. Y.

METHOD OF DELIVERING ILLUSTRATED LECTURES OR SONGS.

Application filed March 1, 1922. Serial No. 540,351.

To all whom it may concern:

Be it known that I, ALEXANDER FERDINAND VICTOR, a subject of the King of Sweden (having declared his intentions of becoming a citizen of the United States), residing at New York, in the county of Bronx and State of New York, have invented certain new and useful Improvements in Methods of Delivering Illustrated Lectures or Songs, of which the following is a full, clear, and exact description.

My invention relates to the method of delivering illustrated lectures or songs by means of wireless telephony.

15 The object of my invention is to project radiogram lectures or songs or anything else, to audiences or persons having wireless receiving stations, and to illustrate the same by pictures projected upon a screen at the place where the lecture is presented. This I accomplish by the means hereinafter fully described and as particularly pointed out in the claims.

20 The drawing illustrates a diagrammatical layout of the invention.

In the drawings A represents a transmitting apparatus that has a receiving horn B, of the usual construction, that is attached thereto by wires C, C', and this transmitting apparatus A is connected by wires D to a wireless transmitting set of wires E.

25 At the receiving end of the invention, there is a receiving set of wires a, that is connected by a wire b to the receiving apparatus c, and this receiving apparatus, c, is connected by wires d and d' to the horn or amplifier e.

At the receiving end of the method, preferably in the same room as the amplifier e, there is a stereopticon screen F, upon which pictures are projected from a stereopticon G by the operator H, during the lecture, that is being delivered by a lecturer, I, into horn B.

30 The lecturer, I, has a castanet J in his hand, and when he desires the pictures changed he simply claps the castanets together, and thus signals the operator for a change. Of course the lecturer could snap his fingers, or could speak his desire for a change. Any means that made a sound that would convey a signal could be satisfactorily employed.

The sound transmitted is preferably of a different timbre from vocal sounds so that the same will not be noticed by the audience, 55 or if heard, will be taken to be interference that is common particularly from signals in code or the like.

It will be understood that, before the lecture, the slides to be displayed by the stereopticon, could be collected and arranged in the order in which they are to be used at a school, or a church, or at home, or other auditorium, where the lecture is to be presented to an audience. 60

65 The foregoing method can be used by any number of receiving stations at the same time, and, could be received by radio stations that were not supplied with the picture apparatus. Such lectures, however, 70 would be enjoyed by audiences to a much less extent, than when illustrated by pictures.

It will be understood that where I refer to lectures I intend to include therein songs, or anything else than can be used by my invention. 75

What I claim as new is:

1. The combination with a wireless sending station from which vocal sounds are transmitted, a receiving station for said vocal sounds, a manually operated picture projecting apparatus located adjacent to the sound reproducer of the receiving station, and a manually controlled signal having a different characteristic from vocal sounds 80 transmitted by wireless to the vicinity of the manually operated picture apparatus for the purpose of signaling to synchronize manually the movement of the pictures to accord with the vocal sounds. 85

2. The combination with a wireless sending station and a receiving station, of a manually operated picture displaying apparatus located adjacent to the receiving station, and means for manually producing at 90 the sending station sounds which serve as signals between the sending and the receiving stations. 95

In witness whereof I have hereunto set my hand this 21st day of February, 1922.

ALEXANDER FERDINAND VICTOR.

Witnesses:

LILLIAN BRUCHHAUSEN,
JOAN HARPER.
